(57) **CLAIM**

The ornamental design for a device for supporting an electronic cigarette, as shown and described.

DESCRIPTION

FIG. 1 is a first perspective view looking in a first direction of a first embodiment of a device for supporting an electronic cigarette;

FIG. 2 is a second perspective view looking in a second direction opposite of the first direction of the first embodiment of the device for supporting an electronic cigarette; FIG. 3 is a front view of the first embodiment of the device for supporting an electronic cigarette;

FIG. 4 is a rear view of the first embodiment of the device for supporting an electronic cigarette;

FIG. 5 is a side view looking towards one side of the first embodiment of the device for supporting an electronic cigarette;

FIG. 6 is a side view looking towards an opposite side of the first embodiment of the device for supporting an electronic cigarette;

FIG. 7 is a top view looking down on the first embodiment of the device for supporting an electronic cigarette; and

FIG. 8 is a bottom view looking up towards the first embodiment of the device for supporting an electronic cigarette.

FIG. 9 is a first perspective view looking in a first direction of a second embodiment of a device for supporting an electronic cigarette;

FIG. 10 is a second perspective view looking in a second direction opposite of the first direction of the second embodiment of the device for supporting an electronic cigarette;

FIG. 11 is a front view of the second embodiment of the device for supporting an electronic cigarette;

FIG. 12 is a rear view of the second embodiment of the device for supporting an electronic cigarette;

FIG. 13 is a side view looking towards one side of the second embodiment of the device for supporting an electronic cigarette;

FIG. 14 is a side view looking towards an opposite side of the second embodiment of the device for supporting an electronic cigarette;

FIG. 15 is a top view looking down on the second embodiment of the device for supporting an electronic cigarette; and,

FIG. 16 is a bottom view looking up towards the second embodiment of the device for supporting an electronic cigarette.
